NUTCRACKER

Carl R. Craft, Kempner, Tex. 76539
Filed July 10, 1972, Ser. No. 270,090

Term of patent 14 years

Int. Cl. D7—04
U.S. Cl. D7—98

Fig. 1

Fig. 2

Fig. 3

Fig. 4

Fig. 5

FIG. 1 is a top plan view of a nutcracker showing my new design;

FIG. 2 is a side elevational view thereof;

FIG. 3 is a bottom plan view thereof;

FIG. 4 is a left end elevational view thereof of FIG. 2; and

FIG. 5 is a right end elevational view thereof of FIG. 2.

I claim:

The ornamental design for a nutcracker, as shown.
